ICE MAKING APPARATUS

Walter G. Kniffin, Dayton, Ohio, assignor to General Motors Corporation, Detroit, Mich., a corporation of Delaware

Filed June 28, 1961, Ser. No. 120,435
5 3 Claims. (Cl. 62—135)

This invention relates to ice makers or ice making apparatuses of the so-called melt-out ice block type and particularly to a thermally operated water valve unit therefor.

Certain types of automatically or semiautomatically operated ice block making machines have not been entirely satisfactory. A machine or apparatus of the type I am referring to is shown and described in the patent to H. W. Clum, #2,407,058, dated September 3, 1946. Such machines are characterized by employment of the so-called melt-out ice block principle wherein incoming water to one empty compartment of a plural or two compartment mold or freezing device is used to warm a wall common to compartments of the mold for thawing and releasing ice blocks from another compartment in the mold and are incapable of fast ice production and for this reason their salability has been retarded. This incapability of these machines is due primarily to insufficient temperature difference between water entering the one compartment and ice previously frozen in the other compartment which requires too much time to effect release of ice blocks from the cold. My invention contemplates an arrangement in ice making machines utilizing the principle stated for increasing the productivity of ice blocks thereby without noticeably affecting the efficiency of a refrigerating system associated therewith.

An object of my invention is to provide an improvement in an ice block making machine or apparatus which will increase the rate at which ice blocks are released from a mold or freezing device thereof.

Another object of my invention is to provide an arrangement for artificially heating a measured body of water from a source of supply thereof outside a freezing chamber housing an ice block maker including a plural compartment mold having a wall between and common to compartments therein prior to discharging the heated body of water into one compartment of the mold for warming its common wall to increase the rate at which ice blocks thaw loose from walls of another compartment of the mold for more rapidly releasing ice blocks therefrom and to cause faster rechilling of the mold and freezing of water in the one compartment thereof.

A further object of my invention is to provide an ice making machine or apparatus of the type herein described with a combined water trapping, measuring and heating unit which discharges a heated body of water into the mold or freezing device thereof in response to a change in temperature of the water being heated.

In carrying out the foregoing object it is a still further and more specific object of my invention to provide the combined water unit with an electric heater energized automatically in response to movement of the mold of the ice machine and with a thermal valve element which is actuated in response to temperatures of water in the unit for discharging heated water therefrom into a compartment of the mold.

Further objects and advantages of the present invention will be apparent from the following description, reference being had to the accompanying drawings wherein a preferred embodiment of the present invention is clearly shown.

In the drawings:

FIGURE 1 is a fragmentary sectional view partly in elevation taken through an insulated refrigerator cabinet

2

containing in a chamber thereof an ice block making and releasing apparatus schematically showing the unit of my invention associated therewith;

5 FIGURE 2 is an enlarged sectional view taken along the lines 2—2 of FIGURE 1 showing the thermal element in my combined water measuring, heating and discharging unit in one position;

FIGURE 3 is a fragmentary sectional view of the thermal element of the water unit shown in FIGURE 2 illustrating the element in another position;

10 FIGURE 4 is a view similar to FIGURE 2 showing the thermal element of the water unit in still another position;

15 FIGURE 5 is a fragmentary sectional view taken along the lines 5—5 of FIGURE 4 showing the anchorage of a spring-biased paddle-like member in the combined unit;

FIGURE 6 is a fragmentary sectional view taken along the lines 6—6 of FIGURE 2 showing the mounting of an electric heater in the water unit; and

20 FIGURE 7 is a diagrammatic view illustrating an electric circuit employed in the present improvement.

As hereinbefore pointed out, my invention relates to an improvement in a particular type of ice making apparatus which may be fully automatic in operation to admit water into a mold thereof, to freeze the water into

25 ice blocks in the mold, to rotate the mold and release ice blocks therefrom and to thereafter repeat this cycle. Such an ice maker and controls therefor is fully shown and described in the Clum patent hereinbefore identified and reference is made to this patent so as to shorten the

30 present specification. The apparatus shown in FIGURE 1 of the drawings is substantially a duplicate of FIGURE 2 of the Clum patent having my combined water measuring, heating, discharging unit and its heater substituted

35 for the water valve and its actuating solenoid respectively disclosed in FIGURE 4 of this patent, except that in my improvement heated water is discharged from the measuring and heating unit in response to a change or increase in temperature of the measured body of water trapped in the unit.

40 In order to render my invention entirely feasible in an apparatus of the type shown in the Clum patent, the ice mold therein may be provided with the additional improvement disclosed in the copending application of P. E.

45 Upchurch, Serial No. 4,354, filed January 25, 1960, entitled "Ice Making Device," now Patent #3,004,405, dated October 17, 1961, and assigned to the assignee of this application. Before proceeding with the description of my invention I desire it to be understood that all

50 reference numerals below 99 herein employed correspond to numerals depicting elements shown and described in the Clum patent, while those numerals above 99 herein employed indicate elements constituting parts of my improvement over this patent.

55 Referring now to the drawings, I show in FIGURE 1 thereof an ice block making apparatus within a freezing chamber of a refrigerator cabinet 10 provided with a combined water trapping, measuring and heating unit, generally represented by the reference numeral 100, located outside chamber 13 beyond the insulation 15 and

60 preferably mounted on the back wall of the refrigerator. This combined unit 100 has a connection 101 with pipe 50 and is connected, by pipe 102, to a source of water supply, under pressure, such as the water main leading into the residence or building in which refrigerator 10

65 is located. Unit 100 (see FIGURE 2) comprises a hollow metal casting or body 104, angularly flanged as at 105, provided with a hollow cover 106, vented at two places, also angularly flanged as at 107. A substantially cup-shaped flexible molded plastic or resilient rubber-like diaphragm 108 has its peripheral edges locked between flanges 105 and 107 of casting 104 and cover 106 respec-

tively by screws or bolts 109 which secure the cover to the casting. The substantially cup-shaped diaphragm 108 is adapted to lie against upright inner wall surfaces of casting 104 and against a metal screen 111 resting on a ledge 112 provided in the casting when unit 100 is not connected to a source of water pressure (see FIGURE 4). A substantially U-shaped wire spring having the end 114 of legs of the U sprung or torsioned and anchored in vent holes 116 bored in cover 106 and is provided with one or more convolutions 117 disposed in hollow bosses 118 of the cover (see FIGURE 5). The anchorage of ends 114 in the holes 116 and the disposition of convolutions 117 of the U-shaped spring in bosses 118 secure this spring in position within unit 100. The base and main parts of leg portions of the U-shaped wire spring are encased in a plastic or the like sleeve member 119, preferably molded thereover, which provides a stiff pivotally movable paddle or blade within unit 100. This molded plastic member prevents the wire spring from biting into and damaging diaphragm 108. This spring tensioned paddle or blade member 119 tends to bias the diaphragm 108 into the position thereof, as shown in FIGURES 4 and 5 of the drawings. A coil resistance type electric heater, generally represented by the reference numeral 120, is enclosed in a nonelectric conducting sleeve and is located within unit 100 below screen 111 therein and its terminal ends 121 and 122 extending through, are secured to and insulated from casting 104 by suitable packing or clamping glands 123 (see FIGURE 6) for connecting the heater into a suitable electric circuit (see FIGURE 7). Heaters of this type are well known and are used as surface heating units on electric stoves or ranges. A boss 126 provided on casting 104 is bored out as at 127 to communicate with pipe 102 and provide unit 100 with a water inlet connection which opens into the hollow chamber of the unit formed by secured-together casting 104 and cover 106. The boss 126 is also bored out to provide a valve seat 128 having a passage therein connected to water inlet 127 and to provide a shoulder 129 against which a washer-like valve plate 131 is abutted. A hollow nut-like plug 132 threaded into boss 126 secures valve plate 131 in position. This plug 132 communicates with the connection 101 and pipe 50 for directing water from combined unit 100 into receptacles or compartments 20 and 21 of mold 19. There is movably located within boss 126 of casting 104 a thermal responsive power element or thermostatic valve means and this element or means may, insofar as the present invention is concerned, be of any suitable or well-known character. It is preferably a means comprising a sealed casing 136 containing a substance such as a wax sealed therein and which wax under certain different temperatures changes its condition from substantially a solid into a liquid and a plunger or piston 137 within and movable relative to or into and out of casing 136 in accordance with the expansion and contraction of the wax substance. Casing 136 of this thermal power element is shiftably interposed between valve seat 128 and valve plate 131 and its movable plunger or piston 137 freely extends through a hole in the washer-like valve plate. A valve 139 is secured to the top of casing 136 and is adapted to cooperate with valve seat 128. An adjustable valve 141 is mounted on the stem of piston 137 and a coil spring 142 is interposed between valve 141 and hollow nut-like plug 132. While the thermostatic means or thermal power element is at room temperature, say, for example between 65° to 85° F., the lower portion of casing 136 thereof rests on valve plate 131 with its piston or plunger 137 contracted into casing 136 whereby spring 142 forces valve 141 against the valve seat or plate 131 to close the opening in the washer-like plate. This is the normal cooled-down position of the thermostatic valve or power element and while in such position water from a source of supply thereof is prevented from passing through the combined unit 100.

According to my invention combined unit 100 is adapted to receive and, by virtue of the predetermined capacity of the hollow chamber part of the unit, measure a body of water to heat the body of water outside the refrigerated chamber or compartment and to then discharge the measured heated body of water into a mold within the chamber of an apparatus of the type disclosed in the Clum patent hereinbefore identified. Assume that unit 100 has been connected to the water supply source, that the refrigerating system associated with the refrigerator has been placed in operation and that upright receptacles of mold 19 have been manually filled, by a pitcher or the like with water to be frozen into ice blocks. Unit 100 is outside insulated walls of refrigerator 10 and thermal responsive power element 136 is at room temperature or is in a cooled-down state, resting on valve plate 131 with its one valve 139 open and with its other valve 141 closed (see FIGURE 2) whereby the pressure of water in the water main 102 has shifted the paddle member within the unit and has caused its chamber to be filled with a measured body of water. As the water initially placed in upright receptacles of mold 19 freezes, thermostatic switch 68 senses the low temperature of the frozen ice blocks in the upright compartments or receptacles of the rotatable mold and closes. Closing of switch 68 completes an electric circuit through a battery 67 (see FIGURE 7) by way of conductors or wires 30a and 30b to energize motor 30 and start rotation of mold 19. Immediately upon initiating rotation of mold 19 roller 58 is cammed upwardly out of a recess in cam 40 to the high side 69 of this cam thereby moving arm 61 of switch 56 up into contact, as indicated by the dotted lines in FIGURE 7, with the stationary switch contact point 70. This completes an electric circuit from battery 67 through a wire 146, switch arm 61, contact 70 and a wire 147 to the terminal wire 122 of heater 120 and from the terminal wire 121 of heater 120 through a wire 148 back to the battery for energizing the water heater of combined unit 100 while mold 19 is being rotated. The remainder of the wiring circuit shown in the Clum patent, except ice storage receptacle circuit breaking switch 82, is not necessary in the present control system because water heater in unit 100 is discharged therefrom in response to a heated temperature thereof therein. With heater 120 energized, during rotation of mold 19 the measured body of water now contained in unit 100 is heated or brought up to a predetermined temperature before mold 19 is rotated 180° and readied to receive, in the rotated empty receptacles, heated water for releasing ice blocks from the inverted compartments or receptacles of the mold. As mold 19 is rotated slightly less than 180° roller 58 drops into another recess in cam 40 which action causes switch arm 61 to move back to its normal location out of engagement with switch contact 70 thus breaking the electric circuit from battery 67 through wires 147 and 148 to heater 120 in unit 100. Heater 120 is of an intensity to insure heating of the measured body of water contained in unit 100, outside the refrigerated chamber, to a temperature of preferably and approximately 140° F., while mold 19 is being rotated a little less than 180°. The thermal power element in unit 100 responds to a temperature of the body of water around 130° F. and at this temperature it extends piston or plunger 137 therefrom to raise casing 136 thereof, against the force exerted by spring 142 without compressing same, upwardly of valve plate 131 within boss 126 and closes valve 139 upon its seat 128. In this manner the body of water contained in unit 100 is trapped therein and the unit is closed off from incoming water at pipe 102. As the temperature of water in unit 100 continues to be increased above 130° F. to approximately 140° F., during rotation of mold 19 and before heater 120 is de-energized, the thermal power element responds to this increased water temperature to further extend piston 137 therefrom and this piston then

overcomes the force of spring 142 and compresses it whereby valve 141 moves away from valve seat 131 to open the passage therein. Opening of valve 141 causes the measured body of water, at a temperature of 140° F. or higher, to flow from combined unit 100 through pipe 50 into the upright receptacles of mold 19. Now with mold 19 rotated 180° and with valve 139 closed and valve 141 opened the U-shaped biasing spring in paddle or blade member 119 shifts same within unit 100 to move the diaphragm 108 downwardly therein (see FIGURE 4) for readying the combined unit to receive another measured body of water when the thermal power element cools to room temperature and moves valves 139 and 141 into the position thereof shown in FIGURE 2 of the drawings. The heated measured body of water is preferably released from unit 100 into mold 19 adjacent the end thereof at which thermostatic switch 68 is located so that the heat of the water is quickly conducted to this switch. The heated water causes switch 68 to open, at the time roller 58 enters the leading end of a recess 40a of cam 40 and receptacles or compartments of tray or plural comparted mold 19 is in a normal horizontal position, thus breaking the circuit through wires or conductors 30a and 30b to de-energize motor 30 and stop rotation of the mold.

The first movements of the thermal responsive power element in unit 100 occur while mold 19 is being rotated and the last movement thereof takes place just prior to the final 180° rotation of the mold. The power element or thermostatic valve in combined unit 100 is shown in FIGURE 2 of the drawings in a position admitting water under, say, for example, 22 to 30 lbs. pressure from the water main supply thereof, pipe 102, into the unit and illustrates the diaphragm 108 shifted upwardly, against the biasing action of spring biased paddle or blade member 119, into engagement with cover 106 so as to fill unit 100 with a metered amount or a measured body of water while valve 141 is seated upon valve plate 131 to prevent flow of the water to pipe 50. In FIGURE 3 of the drawings the thermal element is shown in its first heated and shifted position closing off water inlet 127 to unit 100 and in FIGURE 4 this element is shown in its second heated shifted position, still closing inlet 127 with valve 141 open whereupon the heated measured body of water is caused to be discharged, by spring biased paddle or blade 119, from combined unit 100 through connection 101 and pipe 50 into the mold 19.

At the completion of the cycle of the ice maker above described, ice blocks occupy the downwardly facing receptacles of the back-to-back mold 19 and the heated water fills the upwardly facing receptacles to thereby contact the common wall between the opposed ice block forming receptacles or compartments thereof. The measured body of water now contained in the upright receptacles or compartments is at a heated temperature and its heat is conducted through the common wall, as well as through other walls, of mold 19 to walls of the inverted receptacles or compartments for warming them. This heat melts a thin film of ice where the ice blocks in the inverted receptacles contact walls thereof to thereby thaw ice blocks loose therefrom for releasing them from the mold whereupon the released blocks drop into a storage container or bucket 81 located below mold 19 in the lower portion of compartment 18. If mold 19 is provided with the venting improvement principle disclosed in the hereinbefore identified Upchurch patent, the ice blocks will be caused to drop out of the mold more rapidly. At the end of this complete cycle thermostatic switch 68 is open and remains in this condition until water in the upstanding receptacles or compartments of mold 19 is cooled and frozen at which time switch 68 again senses the low temperature of the ice and closes to initiate another cycle, as described, for continued and successive production of ice blocks by the apparatus. The discharge of heated water into mold 19 affects the efficiency of the refrigerating system asso-

ciated with refrigerator 10 only infinitesimally and advantages derived from utilizing the heated water as herein disclosed greatly outweigh this slight inefficiency.

From the foregoing it should be apparent that I have provided an improvement in ice block making machines or apparatuses which reduces the time required to rid receptacles or compartments of a mold employed therein of ice blocks whereby to relieve the mold of a cold mass, below 32° F., so as to thereby speed up freezing of water and formation of ice blocks in another or other receptacles or compartments in the mold. By my invention I increase the number of ice blocks that can be produced over a given period of operation of an ice making machine without necessarily enlarging the capacity of a refrigerating system associated therewith. My improvement eliminates an inadequacy of a melt-out mold type ice block making apparatus to render same practical and salable and insures a ready supply of ice blocks to be harvested from a refrigerator equipped with such apparatus.

While the embodiment of the present invention as herein disclosed constitutes a preferred form, it is to be understood that other forms might be adopted.

What is claimed is as follows:

1. In an ice making apparatus comprising in combination:

- (a) a chamber cooled to a temperature well below 32° F.,
- (b) a plural comparted mold within said chamber provided with a wall between and common to compartments in said mold,
- (c) one of said compartments being adapted to receive water for warming said common mold wall to effect release of an ice block previously frozen in another compartment of the mold adjacent said one compartment,
- (d) a container outside said chamber for receiving and storing a measured body of water from a source of supply thereof to be admitted to said mold,
- (e) said container being provided with an inlet passage having a pipe connection with said source of water supply,
- (f) said container also being provided with an outlet passage having a pipe connected thereto for conveying water from the container to said mold,
- (g) a single thermostatic element within said container directly contacted by water received therein normally closing its outlet passage and forming without the aid of additional elements the sole means for controlling both said inlet and said outlet passages thereof,
- (h) means for heating water stored in said container to a predetermined temperature, and
- (i) said single thermostatic element being movable in response to a heated temperature of water in the container below said predetermined temperature for closing said container inlet passage and further movable in response to said predetermined temperature of water in the container for opening said container outlet passage whereby the measured body of heated water is discharged into said one compartment of the mold.

2. In an ice making apparatus comprising in combination:

- (a) a chamber cooled to a temperature well below 32° F.,
- (b) a plural comparted mold within said chamber provided with a wall between and common to compartments in said mold,
- (c) one of said compartments being adapted to receive water for warming said common mold wall to effect release of an ice block previously frozen in another compartment of the mold adjacent said one compartment,
- (d) a container outside said chamber for receiving and

- storing a measured body of water from a source of supply thereof to be admitted to said mold,
- (e) said container being provided with an inlet passage having a pipe connection with said source of water supply,
- (f) said container also being provided with an outlet passage having a pipe connected thereto for conveying water from the container to said mold,
- (g) the inlet and outlet passages of said container being aligned with one another,
- (h) a single thermostatic element within said container disposed intermediate the aligned inlet and outlet passages thereof and forming without the aid of additional elements the sole means for controlling said passages,
- (i) said thermostatic element normally closing said container outlet passage and being directly contacted by water received in the container,
- (j) means for heating water stored in said container to a predetermined temperature,
- (k) said single thermostatic element being bodily movable in response to a heated temperature of water in the container below said predetermined temperature thereof in one direction for closing said container inlet passage, and
- (l) said single thermostatic element having a portion movable in a direction opposite said one direction of movement of the portion thereof which closes the container inlet passage in response to said predetermined temperature of water in said container for opening the container outlet passage whereby the measured body of heated water is discharged into said one compartment of the mold.
3. In an ice making apparatus comprising in combination:
- (a) a chamber cooled to a temperature well below 32° F.,
- (b) a plural comparted mold within said chamber provided with a wall between and common to compartments in said mold,
- (c) one of said compartments being adapted to receive water for warming said common mold wall to effect release of an ice block previously frozen in another compartment of the mold adjacent said one compartment,
- (d) a container outside said chamber for receiving and storing a measured body of water from a source of supply thereof to be admitted to said mold,

- (e) said container being provided with an inlet passage having a pipe connection with said source of water supply,
- (f) said container also being provided with an outlet passage having a pipe connected thereto for conveying water from the container to said mold,
- (g) the inlet and outlet passages of said container being aligned with one another,
- (h) a single thermostatic element within said container disposed intermediate the aligned inlet and outlet passages thereof and forming without the aid of additional elements the sole means for controlling said passages,
- (i) said thermostatic element being directly contacted by water received in said container and having a first valve thereon at one end thereof normally closing the container outlet passage,
- (j) means for heating water stored in said container to a predetermined temperature,
- (k) said single thermostatic element having a second valve thereon at the other end thereof,
- (l) said thermostatic element being bodily movable in response to a heated temperature of water in the container below said predetermined temperature thereof for causing said second valve to close the inlet passage to said container while said first valve thereon is closing the container outlet passage, and
- (m) said second valve of said single thermostatic element being movable relative thereto in a direction opposite the direction of bodily movement thereof in response to said predetermined temperature of water in said container for opening the container outlet passage while its inlet passage is closed by said first valve whereby the measured body of heated water only is discharged into said one compartment of the mold.
